UNITED STATES PATENT OFFICE.

JAMES CUMMING, OF JERSEY CITY, NEW JERSEY.

IMPROVEMENT IN GAGE-COCKS.

Specification forming part of Letters Patent No. **157,583**, dated December 8, 1874; application filed May 12, 1874.

To all whom it may concern:

Be it known that I, JAMES CUMMING, of Jersey City, in the county of Hudson and State of New Jersey, have invented an Improvement in Gage-Cocks, of which the following is a specification:

This invention relates to that class of gage-cocks in which, by means of a pipe attached to the revolving plug or spindle of the cock, and bent or set at an angle to the axis thereof, a single cock is enabled, by turning its plug or spindle, to serve the purpose of ascertaining the level of the water in a boiler.

This invention consists in forming the shell of the stop-cock with a boss, into which is fitted a screw-plug, the shell, the boss, and the screw-plug having an oblique passage through the same, to the lower end of which is secured a straight pipe, so that it will be brought to a position in line with the said oblique passage, whereby a straight wire can be passed through said passage, and through the straight pipe, with ease and facility, for the purpose of cleaning the same—a result which cannot be effected if a curved pipe be used, for a flexible wire would have then to be employed.

In the accompanying drawing, Figure 1 is a central vertical section of a gage-cock embodying my improvements. Fig. 2 is a side elevation.

A represents the shell of the cock, provided with a screw-thread on its inner portion for attaching it to the boiler B. On the upper side of the shell A is a boss, A', through which is formed an oblique passage, a, communicating with the center cavity or bore of the shell. Into this boss is screwed a socket, C, which forms a continuation of the passage a, and into the outer end of which is screwed a screw-threaded plug, D, provided with a handle, d, for turning it. The inner end of the plug D is made conical to form a valve, v, and fits in a corresponding seat in the socket C, near which seat is an orifice, e, which allows the steam or water to escape when the plug D is unscrewed to remove the valve from its seat, and which is closed when the plug is screwed up to its seat, as shown in Fig. 1.

The shell A has running axially through it the revolving plug or spindle E, on the outer end of which is a lever, f, which serves as a handle, and also as an indicator. The inner end of this revolving plug or spindle is bent and bored out, so as to form a passage, e, which will form a continuation of the passage a of the shell when in line therewith. To the inner end of the bent portion is attached a pipe, G, which forms a prolongation of the pipe e in the plug or spindle to a sufficient length to reach the various levels of the surface of the water. The inner end of the plug or spindle E is enlarged in valvular form, as shown at t, Fig. 1, to fit to a seat, which may be either conical or of rabbet form in the inner end of the shell, and the outer end is provided with a spring, g, between the lever f and the stuffing-box h, to prevent an accidental longitudinal movement of the plug or spindle. At the point where the passage e meets the passage a in the shell the spindle E has a groove, l, on its periphery, forming a continuous channel or chamber for the passage of steam or water, so that, when the shaft E is turned to bring the passage e out of line with the passage a, there will still be a continuous communication between the passages e and a, and the water or steam is allowed to pass freely through the same when the valve v is open. The shaft E is turned by means of the handle f, so as to bring the inner end of the pipe G to any desired level, in order to ascertain the height of water in the boiler.

When it is desired to clear out the passages a e the plug D is to be entirely removed, and the passage may then be cleared of any obstruction which may exist by turning the spindle E to a position to bring its pipe G and passage e in line with the passage a of the shell, and inserting a wire or other device directly through the two passages; and thus, by the employment of the straight pipe, it will be seen that I am enabled to employ a straight rod or wire, which could not be employed if a curved pipe were used.

Instead of the removable plug D for closing the passage a, there may be a revolving trans-

verse plug, with a passage through it like the plug of a stop-cock.

What I claim as new, and desire to secure by Letters Patent, is—

The boss A', socket C, plug D, and the shell A, in combination with the oblique passages a e, shaft E, groove l, and straight pipe G,

substantially as described, whereby the pipe is brought in line with the passages a e, as herein shown, for the purposes specified.

JAMES CUMMING.
